United States Patent Office

Des. 185,853
Patented Aug. 11, 1959

185,853

GIRDLE

Joy Seay Darcey, Palo Alto, Calif., assignor to Beverly
Vogue Company, Los Angeles, Calif., a firm

Application September 17, 1957, Serial No. 47,764

Term of patent 14 years

(Cl. D20—2)

Fig. 1 is a front side view, in elevation, of a girdle embodying my invention;

Fig. 2 is a rear side view, in elevation, thereof; and
Fig. 3 is a perspective view thereof.

The dominant features of my new design are shown in solid lines.

I claim:

The ornamental design for a girdle, as shown and described.
